CLAIM

The ornamental design for a compact disc storage container, as shown and described.

DESCRIPTION

FIG. 1 is a perspective view of a compact disc storage container shown in a partially open position;

FIG. 2 is a front elevational view thereof shown in a closed position;

FIG. 3 is a rear elevational view of FIG. 2;

FIG. 4 is a top plan view of FIG. 2;

FIG. 5 is a bottom plan view of FIG. 2;

FIG. 6 is a top plan view thereof, shown in a fully open position;

FIG. 7 is a right side elevational view of FIG. 2, the left side being a mirror image; and,

FIG. 8 is a right side elevational view of FIG. 6.
